REPRODUCING AND PROJECTING APPARATUS

Samuel Blanc, Grantwood, N. J.

Application July 29, 1944, Serial No. 547,248

6 Claims. (Cl. 88—24)

1

This invention relates to reproducing and projecting apparatus, and more particularly to apparatus of this type which is adapted to readily obtain scaled images of drawings, prints, maps or the like, or of various articles of manufacture, such as machine parts.

The apparatus of this invention may be employed in drafting rooms or other locales and has a variety of uses. For example, a scaled image of an object may be cast on a translucent panel and readily traced by hand or reproduced on a sensitized film or the like from which subsequent blueprints or copies may be made.

To this end my instant invention comprises a cabinet that is open at the top, above and across which there is provided a table board having a translucent panel. The table board is vertically adjustable and is tilttable on a substantially horizontal axis. The interior of the cabinet is divided into a lower or light compartment and an upper or lens compartment. An object-holder is mounted on a sliding shelf that forms the bottom wall of the cabinet. The object-holder is rotatable on a substantially vertical axis and is also tilttable on a substantially horizontal axis whereby an object, such as a drawing or an article of manufacture, may be placed thereon and arranged in any predetermined desired position.

A pair of tubular lamps are positioned in the light compartment above and to the side of the object-holder and are provided with suitable reflectors that are adapted to direct light rays to the object-holder. The light rays so directed to the object-holder are reflected upwardly into the lens compartment. A lens assembly is contained within the lens compartment. This assembly includes a lens plate whose plane may be arranged either horizontally or vertically. The lens plate has a central aperture and a plurality of lenses of different focal length pivotally supported on its upper surface. The individual lenses are so constructed and arranged that only one thereof at a time registers with the aperture in the lens plate. The lens plate is adapted to be raised and lowered within its compartment by a suitable mechanism, including vertically disposed racks and pinions and an actuating means manually operable from the exterior of the cabinet.

A projector is removably mounted to a side wall of the cabinet and cooperates with the lens assembly to project an image on a substantially horizontal axis through the cabinet when the lens plate is in one predetermined position.

By the practice of my invention exact reproductions of various objects may be directly ob-

5 tained. Additionally, perspective or isometric drawings or reproductions of articles of manufacture may readily be obtained by the practice of this invention, as will be apparent to persons skilled in the art from the detailed description that follows.

In the design and manufacture of certain items of equipment, such as in the airplane field, it is customary to first prepare small scale drawings from which actual size templates are drawn by hand. This is a laborious procedure and consumes considerable time. By the use of the apparatus of this invention, a full size image of the small-scale drawing may be projected and traced to obtain the template direct. If desired, this image may be projected upon a light sensitive material to obtain a full size reproduction without the necessity of drawing or tracing.

It is an object of this invention to provide apparatus of the character indicated which is adapted to readily obtain enlarged or reduced reproductions of various articles including drawings, prints and the like.

Another object of this invention is to provide reproducing and projecting apparatus that may be readily adjusted to obtain images of various objects at any desired angle and/or size.

This invention has for another object the provision of apparatus of the type indicated which is adapted to obtain perspective or other three dimensional reproductions of an article.

A further object of this invention is the provision of reproducing and projecting apparatus which is relatively simple and compact in design, sturdy in construction, and trouble-free in operation.

The foregoing, as well as other objects, will be readily apparent to persons skilled in the art by reference to the following detailed description and annexed drawings which respectively describe and illustrate a preferred embodiment of the invention, and wherein

Figure 1 is a perspective view of one arrangement of apparatus comprising the instant invention;

Figure 2 is a vertical sectional view along line 2—2 of Figure 1;

Figure 3 is a vertical sectional view along line 3—3 of Figure 1;

Figure 4 is an enlarged fragmentary view in perspective depicting the lens assembly and adjusting means;

Figure 5 is a perspective view of a cover arrangement mounted on the table of the apparatus of Figure 1 and shown in open position;

Figure 6 is a perspective view of an adapter mounted on the apparatus of Figure 1;

Figure 7 is a view similar to Figure 3 and illustrating the lens plate in vertical position; and

Figure 8 is a perspective view in enlargement of a portion of the rear wall of the cabinet showing a slide panel in place of the projector of Figure 3.

Referring to the drawings, and more particularly to Figures 1, 2 and 3 thereof, the numeral 10 generally denotes a cabinet that is open at the top and that includes a base pedestal 11. Above and across the cabinet top there is disposed a work table 12 that is provided with a central opening 13 within which there is a translucent panel 14 which may be transparent and which is composed of a suitable glass or similar material. The work table carries a pair of depending brackets 15. A tubular member 16 is open at each end and is telescopically positioned in the upper part of the cabinet. Bolts 17 extend through opposite walls of tubular member 16 and brackets 15 to thereby pivotally connect the work table to the tubular member. Each bolt is provided with a wing nut 18 for maintaining the work table in desired tilted position with respect to the cabinet. Suitable roller or ball bearings 19 are provided to minimize friction and facilitate the raising and lowering of tubular member 16 with respect to the cabinet.

The tubular member and the work table 12 are raised and lowered along a substantially vertical path at the will of the operator by a mechanism which will now be described. This mechanism includes a hand-crank 20 that is connected to a shaft 21 which carries a pair of driving gears 22 that mesh with driven gears 23 rotatably mounted on stub shafts 24 as best shown in Figure 3. Also mounted on stub shafts 24 are sprocket wheels 25. Corresponding sprocket wheels 26 are mounted on stub shafts 27. Endless chains 28 cooperate with corresponding sprocket wheels 25 and 26 in the usual manner. Each chain 28 carries a bracket or connector 29 that engages a part of the tubular member. Upon actuation of hand-crank 20, shaft 21 is rotated and the various gears and sprocket wheels cooperate with endless chains 28 to move connectors 29 and tubular member 16 either upwardly or downwardly to thereby adjust the vertical position of table board 12. Cabinet 10 is provided with slots 30 through which locking members 31 project for engagement with sprocket wheels 26 to lock the sprocket wheels at the will of the operator.

The front wall of the cabinet carries a door 32 that is hinged at its side edge and a door 33 that is hinged at its bottom edge. A partition 34 having a central opening 35 divides the interior of the cabinet into a lower or light compartment 36 and an upper or lens compartment 37. A removable shelf 38 is slidable into the lower portion of the cabinet on rails 39 and constitutes the bottom wall of the cabinet. Reference numeral 40 generally denotes an object-holder assembly preferably consisting of a turret 41 rotatable on a substantially vertical axis and formed with a member 42 that extends into and is pivotally coupled to a bifurcated member 43 by a bolt 44. An object-holder plate 45 is carried by member 43. A handle 46 constituting an extension of bolt 44 permits of rotation of the object-holder plate about the axis of turret 41.

Reference is now had to Figures 1, 2, 4 and 7 for a full understanding of the lens assembly of

this invention. This includes a support 50 that is secured to the rear wall of the cabinet and that is provided with a pair of vertical grooves 51 which receive bent-over portions 52 of a pair of arms 53. The front face of support 50 carries a pair of vertical racks 54 which mesh with pinions 55 that are secured to a shaft 56 which extends through arms 53 and a vertical slot 57 in a side wall of the cabinet. A hand knob 58 for imparting rotation to shaft 56 is connected to the outer end of said shaft. A knurled lock nut 59 is in threaded engagement with shaft 56 and serves to lock said shaft in desired vertical position. Each arm 53 is provided with an elongated notched slot 60 and an elongated bayonet slot 61. A lens plate 62 is disposed between arms 53 and is provided with pins 63 that extend through slots 60. Threaded pins 64 extend laterally of plate 62 and are adapted to be received in bayonet slots 61. Wing nuts 65 engage pins 64 and serve to lock lens plate 62 in the position shown in full lines in Figure 4. By loosening wing nuts 65 and moving lens plate 62 toward the rear of the cabinet, pins 64 are disengaged from bayonet slots 61 and the lens board is pivoted by gravity to the position shown in dotted lines in Figure 4 or to any intermediate position, as desired. The lens board is provided with a central opening 66. A plurality of lenses 67, 68 and 69 of different focal length are pivotally supported to the upper surface of the lens plate and are adapted to be locked in predetermined position by lock nuts 70, 71 and 72, respectively. These lenses are so constructed and arranged that only one of them at a time may be pivoted to a position whereby it will register with opening 66 in the lens plate. As shown in Figures 2, 3 and 4, lens 68 alone registers with opening 66.

A pair of tubular electric lamps 75 are mounted above and to the side of object-holder 45 within light compartment 36. Each lamp is connected to a suitable source of electricity (not shown) and is provided with a combined light housing and reflector 76 having ventilation apertures 77 and an arcuate shade 78. As is best shown in Figure 2, light rays from lamps 75 are directed onto object-holder 45 by reflectors 76. The light rays are then reflected through opening 35 in partition 34, through opening 66 in lens plate 62, and thence through lens 68, whence they are directed to translucent panel 14.

A shelf 80 is hinged to the rear wall of cabinet 10 and is adapted to be supported in a substantially horizontal position by means of at least one collapsible bracket 81. A projector, generally indicated by numeral 82, is supported on shelf 80 and includes a main housing 83, a lamp 84, a ventilator hood 85, a slot 86 for receiving an object plate frame 87, and a bellows 88. Bellows 88 is connected to a frame 89 and registers with an opening 90 in the rear wall of the cabinet. A circular opening 91 is provided in door 32 directly opposite opening 90 in the rear wall of the cabinet. Opening 91 is normally closed by closure 92 that is pivotally supported to door 32 at 93. When projector 82 is not in use, it may be removed from the cabinet and bracket 81 may be collapsed to permit shelf 80 to assume the position indicated by the dotted lines in Figure 3. Also, a slidable panel closure 94 (see Fig. 8) is inserted in frame 89 to cover opening 90.

When projector 82 is in service, lens board 62 is adjusted to the position illustrated in full lines in Figure 7 and in dotted lines in Figure 4. At such times closure 92 is pivoted away from open-

ing 91 in door 32. The lens board is adjusted vertically until the axes of openings 66, 90 and 91 coincide whereby light rays transmitted through opening 90 by projector 82 pass through opening 66 and the lens registering therewith, and then pass through opening 91 whence they are projected on a screen, a sensitized material or the like (not shown) as is indicated in Figure 7.

In Figure 5 I have illustrated a table board cover 95 that includes an elongated U-shaped fitting 96 engaging an edge of the table board, and a frame consisting of a pair of parallel arms 97 and a cross piece or handlebar 98. Each arm 97 is provided with a slot 99. The cover proper is indicated by numeral 100 and consists of a plurality of wood slats 101 mounted on a cloth backing 102 that is joined at its lower edge to fitting 96. The upper portion of cover 100 is secured to a pair of pins 103 which are slideable in slots 99 and are provided at their free ends with removable knobs 104. A cushion 105 of rubber or the like is provided between arms 97 and cover 100 to absorb impact shocks when the cover is lowered upon the work table. It will be observed that cover 95 is substantially co-extensive with the surface of the table board.

An adapter for the work table is shown in Figure 6 and comprises a panel 106 that has a central opening (not shown) and that is connected at one end to a U-shaped fitting 107 which engages an edge of the work table. The opposite end of the adapter panel carries a pair of upwardly projecting pins 108. A removable U-shaped fitting 109, adapted to slip over adapter panel 106 and the edge of the work table, is formed with a pair of bayonet slots 110 for receiving pins 108. A frame 111 that is open at one end is mounted on panel 106 directly above translucent panel 14 of the table board. A frame 112 carrying a ground-glass plate 113 is coupled to frame 111 by a plurality of hinges 114. Leaf springs 115 are attached to the upper surface of frame 111 and bear upon hinges 114. Hinges 114 permit the introduction of a film-holder 116 between adapter panel 106 and frame 112 against the action of leaf springs 115. This arrangement permits the operator to obtain an enlarged or reduced reproduction of the object supported on the object-holder on a sensitized plate 117 in film-holder 116.

Based on the foregoing description, it is believed that the objects, advantages and operation of this invention will be readily comprehended by persons skilled in the art. It is to be understood, however, that various changes in the apparatus herewith illustrated and described may be resorted to without departing from the spirit of this invention or the scope of the appended claims.

I claim:

1. In apparatus of the character described, a cabinet having an open top, a table disposed above and across said top and including a translucent panel, said table being pivotally supported on a substantially horizontal axis, means for raising and lowering the table with respect to the cabinet, an object-holder in the lower portion of the cabinet, means for tilting the object-holder, means for directing light rays onto the object-holder, and lens means positioned in the cabinet intermediate the object-holder and the table, said lens means comprising a plate, an opening in the plate, and a plurality of lenses having different focal lengths, said lenses being independently and pivotally secured to the plate and being

so constructed and arranged that only one thereof at a time may be pivoted so as to register with the opening.

2. In apparatus of the character described, a cabinet having an open top, a table disposed above and across said top and including a translucent panel, said table being pivotally supported on a substantially horizontal axis, means for raising and lowering the table with respect to the cabinet, an object-holder in the lower portion of the cabinet, means for tilting the object-holder, means for directing light rays onto the object-holder, and substantially vertically and horizontally movable lens means positioned in the cabinet intermediate the object-holder and the table, said lens means comprising a plate, an opening in the plate, and a plurality of lenses having different focal lengths, said lenses being independently and pivotally secured to the plate and being so constructed and arranged that only one thereof at a time may be pivoted so as to register with the opening.

3. In apparatus of the character described, a cabinet having an open top, a table disposed above and across said top and including a translucent panel, means for raising and lowering the table with respect to the cabinet, an object-holder in the lower portion of the cabinet, means for rotatably supporting the object-holder on a substantially vertical axis and for tilting the object-holder on a substantially horizontal axis, means for directing light rays onto the object-holder, and substantially vertically movable lens means positioned in the cabinet intermediate the object-holder and the table.

4. In apparatus of the character described, a cabinet having an open top, a table disposed above and across said top and including a translucent panel, said table being pivotally supported on a substantially horizontal axis, means for raising and lowering the table with respect to the cabinet, an object-holder in the lower portion of the cabinet, means for rotatably supporting the object-holder on a substantially vertical axis and for tilting the object-holder on a substantially horizontal axis, means for directing light rays onto the object-holder, and substantially vertically and horizontally movable lens means positioned in the cabinet intermediate the object-holder and the table, said lens means comprising a plate, an opening in the plate, and a plurality of lenses having different focal lengths independently and pivotally secured to the plate and being so constructed and arranged that only one thereof at a time may be pivoted so as to register with the opening.

5. In apparatus of the character described, a cabinet having an open top, a table disposed above and across said top and including a translucent panel, a removable sliding shelf in the lower portion of the cabinet, an object-holder rotatably supported by and above the shelf on a substantially vertical axis, means for tilting the object-holder on a substantially horizontal axis, and lens means positioned in the cabinet intermediate the object-holder and the table, said lens means comprising a plate, an opening in the plate, and a plurality of lenses having different focal lengths, said lenses being independently and pivotally secured to the plate and being so constructed and arranged that only one thereof at a time may be pivoted so as to register with the opening.

6. In apparatus of the character described, a cabinet having an open top, a table disposed

above and across said top and including a translucent panel, a removable sliding shelf in the lower portion of the cabinet, an object-holder rotatably supported by and above the shelf on a substantially vertical axis, means for tilting the object-holder on a substantially horizontal axis, and substantially vertically and horizontally movable lens means positioned in the cabinet intermediate the object-holder and the table, said

lens means comprising a plate, an opening in the plate, and a plurality of lenses having different focal lengths, said lenses being independently and pivotally secured to the plate and being so constructed and arranged that only one thereof at a time may be pivoted so as to register with the opening.

SAMUEL BLANC.
